CLAIM

The ornamental design for an earphone box, as shown and described.

DESCRIPTION

FIG. 1 is a front perspective view of an earphone box showing my design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

(Continued)

FIG. 9 is a front perspective view of the earphone box showing my design, showing the earphone box in an open position.

The broken lines in the figures show portions of the earphone box that form no part of the claimed design.
